DESIGN FOR A BAG FASTENER OR SIMILAR ARTICLE

Truman Kenneth Jamison, Hoquiam, Wash.

Application May 12, 1942, Serial No. 106,871

Term of patent 3½ years

To all whom it may concern:

Be it known that I, Truman Kenneth Jamison, a citizen of the United States, residing at Hoquiam, in the county of Grays Harbor, and State of Washington, have invented a new, original, and ornamental Design for a Bag Fastener or Similar Article, of which the following is a specification, reference being had to the accompanying drawing, forming part thereof.

Figure 1 is a side elevational view of a bag

fastener or similar article showing my new design.

Figure 2 is a top plan view.

Figure 3 is an end elevational view, and

Figure 4 is a view similar to Figure 1 showing the fastener in open position.

I claim:

The ornamental design for a bag fastener or similar article, as shown.

TRUMAN KENNETH JAMISON.
